Primary Examiner — Ian Simmons*Assistant Examiner* — Lauren D McVey(74) *Attorney, Agent, or Firm* — Merchant & Gould P.C.(57) **CLAIM**

The ornamental design for a training device for minimally invasive medical procedures, as shown and described.

DESCRIPTION

FIG. 1 is top isometric view of a training device for minimally invasive medical procedures, showing our new design;

FIG. 2 is another top isometric view thereof;

FIG. 3 is another top isometric view thereof;

FIG. 4 is another top isometric view thereof;

FIG. 5 a right side view thereof;

FIG. 6 is a left side view thereof;

FIG. 7 is a rear view thereof;

FIG. 8 is a front view thereof;

FIG. 9 is a top view thereof; and,

FIG. 10 is a bottom view thereof.

The wire frame lines shown throughout the views are intended to indicate surface contour. The stippled shading represents a contrast in appearance.

1 Claim, 10 Drawing Sheets(56)
